UNITED STATES PATENT OFFICE.

GIUSEPPE RESTUCCI, OF NAPLES, ITALY.

STEAM DRYING AND SUPERHEATING SYSTEM.

1,157,901.

Specification of Letters Patent. Patented Oct. 26, 1915.

Application filed June 30, 1914. Serial No. 848,149.

To all whom it may concern:

Be it known that I, Giuseppe Restucci, a subject of the King of Italy, residing at Naples, Italy, mechanical engineer, whose post-office address is No. 156 Corso Garibaldi, Naples, have invented certain new and useful Improvements in or Relating to Steam Drying and Superheating Systems, of which the following is a specification.

My invention relates to apparatus in which the drying and superheating of the steam is effected by throttling.

According to my invention the throttling of the steam is effected by means of one or several sets of nozzles having suitable shapes and dimensions, and distributed in suitable positions along the main pipe of a steam plant between the boiler and the place of consumption. Said nozzles are constructed in the shape of a truncated cone having the small base slightly flaring. The dimensions and the number of these nozzles are so selected that, according to its degree of wetness the steam by being throttled through the nozzles is converted into a saturated or superheated state.

According to my invention the steam is caused to enter into the nozzles through the larger base of the cone; the nozzles are, moreover mounted in such a way that their axes approximately lie in the path of the flowing steam.

In the accompanying drawings Figure 1 is a side view of a steam outlet pipe, provided with said nozzles and adapted to be placed in the steam space of a boiler drum. Fig. 2 is a sectional view of a steam valve provided with said nozzles. Fig. 3 is a side sectional view of another form of steam valve provided with said nozzles.

In Fig. 1, A is the outlet steam pipe to be mounted in a boiler drum. The end B is closed so that the steam is obliged to pass through the nozzles 1, then passing out through the open end C into an ordinary steam pipe mounted between the boiler and the place of consumption.

Fig. 2 shows a compound valve applied to a boiler D, --3-- is the external valve casing, --2-- is an internal casing with a number of nozzles --1-- grouped in three or more parallel rows, --5-- is a valve piston bearing against the seat 11, --4-- is a cylindrical piston provided with parallel apertures --10-- and adapted to slide on the internal

surface of the casing 2. These pistons are connected together by a rod --6--; the latter being controlled by the handwheel --9-- through the conical gears 7 and 8. The steam enters first into the chamber E and afterward through the valve --5-- into the chamber F and then through the nozzles 1 into the pipe G. The apertures --10-- provided in the cylindrical piston 4 are so disposed as to successively expose each row of nozzles while piston --4-- is displaced.

The pistons --4-- and --5-- are simultaneously moved in such a way that the size of the passage of the steam from the chamber E into the chamber F will be proportioned to the number of open nozzles.

Fig. 3 shows the application of my invention to an ordinary double seat valve. This valve is provided with a cylindrical piston --18--, adapted to slide on the internal surface of the casing --2--, which has a number of apertures cut in its cylindrical surface. The casing 2 is provided with several sets of nozzles. The height of the apertures and the intervals between them are so proportioned as to expose gradually each row of nozzles. The valve piston --14-- of the double seat valve is provided with a flange adapted to bear against the collar of piston --18-- when piston 14 is moved upward in Fig. 3. When the piston 14 has reached a certain height, the valve piston 16 is also moved upward by means of one of the well known cam devices usually employed for such valves. The upward movement of the valve pistons is made to correspond to the opening of a predetermined number of nozzles.

The valve just described can be mounted on the main pipe of a steam plant of course in any suitable way and in any suitable position, between the boiler and the place of consumption and it will be understood that in all the constructions shown the steam by being caused to pass through the nozzles provided in its path of flow will be throttled and thereby made to give up its moisture so that a dry or even a superheated steam will be obtained.

Having now particularly described and ascertained the nature of my said invention and in what manner the same is to be performed, I declare that what I claim is:

1. In combination with a steam conduit, a set of nozzles having the shape of truncated cones mounted on said conduit with their

axes lying in the path of the flowing steam, the nozzles with their wider base projecting from said conduit.

2. In combination with a steam conduit, 5 a set of nozzles having the shape of truncated cones with their smaller base slightly flaring mounted on said conduit with their axes lying in the path of the flowing steam, the nozzles with their wider base projecting 10 from said conduit.

3. In combination with a steam conduit, a plurality of rows of nozzles mounted on 15 said conduit with their axes lying in the path of the flowing steam and having the shape of truncated cones with their wider portions projecting from said conduit, and means for successively exposing said rows of nozzles.

4. In combination with a steam conduit, 20 and a steam valve located therein and comprising an outer and an inner casing spaced apart from each other, a plurality of rows of nozzles mounted in said inner casing in the path of the flow of the steam and shaped 25 like truncated cones with their wider base projecting from said inner casing into the space between the said two casings, and an

apertured valve in said inner casing adapted to successively expose the various rows of nozzles.

5. In combination with a steam conduit and a steam valve located therein and comprising an outer and an inner casing spaced apart from each other, a plurality of rows of nozzles mounted on said inner casing in the 35 path of the flow of the steam and shaped like truncated cones with their wider base projecting from said inner casing into the space between the said two casings, an apertured valve in said inner casing adapted to successively expose the various rows of nozzles, and a valve for controlling the admission of steam to the space between the said inner and outer casing, and means connecting said two valves to insure their simultaneous operation.

In testimony whereof I have signed my name to this specification in presence of two subscribing witnesses.

GIUSEPPE RESTUCCI.
